UNITED STATES PATENT OFFICE.

LEONARD ANGELO LEVY, OF CRICKLEWOOD, ENGLAND.

NOZZLE FOR THE PRODUCTION OF ARTIFICIAL FILAMENTS.

No Drawing. Application filed August 16, 1926, Serial No. 129,660, and in Great Britain September 14, 1925.

This invention relates to improvements in connection with nozzles for the production of artificial filaments.

In the production of artificial filaments, especially in processes where a fine filament is extruded at high pressure, it is necessary to provide very fine, strong uniform orifices through which the material is forced.

10 To obtain efficient results, such orifices must comply with certain conditions. For example, they must be of uniform diameter they must offer uniformity of resistance to the flow of the extruded material, and they 15 must withstand wear.

The material which best conforms to these requirements is glass, which is preferable to metal, from which latter material it is very difficult to make orifices of very fine diameter through more than a very small thickness. In addition the wear on glass is considerably less and it causes less frictional resistance to the flow of the extruded material.

A known method of making such orifices 25 is to select carefully by means of microscopic examination, glass capillary tubing of exactly the diameter required, which may be, say, 0.1 or 0.08 m. m. and to seal to a small portion of such capillary tubing a piece of 30 tube of somewhat larger diameter, to provide the lead-up for the attachment of the jets to the nozzle-heads.

It is obvious that the flow from such nozzles will vary according to the length 35 of the capillary tubing and to the exact shape of the capillary "lead-up" i. e. that portion of the capillary which is enlarged for attachment to the wider glass.

Now, according to my invention in order that the jets shall interpose exactly the same 40 resistance to the flow of the extruded material, I force water, oil, or other suitable liquid under considerable pressure through the nozzles which have increasing bores, whilst they are being ground down across 45 the openings by means of a carborundum or suitable grinding stone. Measurements of the total flow in a given time at intervals are made and the grinding is continued until the flow in a given interval through the jet reaches a definite fixed value. I have found 50 that the most efficient means of holding these jets during the grinding operation, is by hand, and while any suitable means of measuring may be employed for ascertaining 55 the rate of flow of water or oil when determining the jet size, I prefer to measure the quantities passed in a given time by removing the jet from the stone at predetermined intervals, and collecting the liquid in 60 a Burette. By these means all the jets are made of exactly the same flow value and in addition there is no liability of the capillary-bore being stopped up by the process of 65 grinding.

Claim:

The method of determining the varying diameter of a tapered orifice, in a nozzle being ground, which consists in passing a fluid through said orifice under a predetermined pressure, and measuring the quantity of said fluid passed therethrough in a given time at predetermined intervals.

LEONARD ANGELO LEVY.
